CONTAINER AND RIM THEREFOR

Chester M. MacChesney, Chicago, Ill., assignor to
Acme Steel Company, Chicago, Ill., a corpora-
tion of Illinois

Application June 13, 1934, Serial No. 730,413

4 Claims. (Cl. 217—89)

This invention relates to improvements in containers and rims therefor and its purpose is to provide an improved container, preferably of polygonal cross-section, having a novel form of reinforcing metal rim around one or both ends thereof. The improved container is constructed principally of wood and comprises a plurality of outer wall sections arranged preferably in octagonal form and bound together to form a vessel adapted for use as a substitute for barrels and the like in which goods are packed for shipment. The outer walls of the container are preferably reinforced and bound together by surrounding binding wires which have their outer ends twisted or otherwise secured together, with the intermediate portions thereof stapled or otherwise fastened to the separate wall sections. The outer wall thus formed is closed at its ends by end walls or heads, one or both of which are secured in place by the improved metal rim of the present invention which has an annular portion extending around the outer walls of the container and inwardly extending flanges which overlap the adjacent head or end wall. The principal object of the present invention is to provide an improved sheet metal rim of polygonal form comprising portions adapted to engage and conform to the sides of the container and having flanged portions which are adapted to fit closely the adjacent end wall or head. A further object of the invention is to provide a metallic rim of polygonal form having an inwardly extending flange which is transversely corrugated. Still another object of the invention is to provide a metallic rim of polygonal form having parts adapted to conform to the outer walls of a vessel and having inwardly extending corrugated flanges in which the corrugations are of varying configuration from end to end of each flange in order to permit the flange to fit closely against the head or end wall without destroying the true polygonal relationship of those portions of the rim which are adapted to engage the outer wall sections of the container. A further object of the invention is to provide a reinforcing metallic rim of polygonal form having angularly disposed body portions adapted to fit closely against the side walls of a container and having inwardly extending integrally united flanges adapted to fit against the end wall or head, these flanges being transversely corrugated with the corrugations tapered adjacent the points where the flanges are united with each other. Other objects relate to various features of construction and arrangement which will appear more fully hereinafter.

The nature of the invention will be understood from the following specification taken with the accompanying drawing, in which one form of container embodying the improved rim of the present invention is illustrated. In the drawing,

Fig. 1 is a perspective view of a container embodying the improved rim of the present invention with a portion of the container broken away;

Fig. 2 shows a partial enlarged vertical section taken on the line 2—2 of Fig. 1; and

Fig. 3 is a perspective view of a portion of the rim when removed from the remaining parts of the container.

As illustrated in the drawing, the invention is embodied in a container 15 which comprises a plurality of vertical side wall sections 16 which are so arranged that the container has an octagonal horizontal cross-section. For this purpose, each side wall section 16, which is constructed preferably of wood, is beveled along its opposite upright edges as shown at 16^a and the inclination of these beveled surfaces is such that one beveled edge of each wall section may be arranged to fit within the edge of one of the next adjacent wall sections and to contact therewith, as shown in Fig. 1, while the other edge is located on the outer side of the other next adjacent wall section with the beveled edge at that side lying in the same plane as the wall section immediately adjacent thereto. The wall sections thus have a progressive overlapping relationship around the container. At their lower ends, the wall sections 16 have a plurality of separate cleats 17 secured thereto and at their upper ends these wall sections have another series of cleats 18 secured thereto. All of these cleats are located on the inner sides of the wall sections and the end surfaces of the cleats are so beveled that when the wall sections are arranged in polygonal form, as shown in Fig. 1, the ends of adjacent cleats in each series contact closely with each other. A bottom wall 19, of octagonal form, fits within the side wall sections 16 and rests upon the lower cleat 17, as shown in Fig. 1. All of these walls are held in assembled relationship by surrounding flexible binders 20 which may be in the form of binding wires secured to the several side wall sections by staples 21 and having their ends twisted or otherwise secured together as shown at 22. At the upper and lower ends of the container, the staples 21 serve also to secure the cleats 17 and 18 to the wall sections and, if desired, nails 23 may also be employed for securing the cleats in place.

The various wall sections 16 may be secured to the binding wires and to each other by means

of the staples 21 at the place of manufacture, as is usual in the manufacture of wire-bound boxes and the like, and a large number of assembled units of wall sections may be superimposed upon each other and shipped as a bundle to the place where the containers are to be assembled and filled for shipment. A series of connected wall sections 16 may then be assembled, the ends of the wires 20 twisted together and the bottom wall 19 put in place, preferably by being inserted before the outer walls are secured in assembled relationship by uniting the ends of the wires, and then the container is ready to be filled. After the container has been filled with the commodity to be shipped therein, the upper end of the container is closed by a cover or top wall 25 which is preferably in the form of a wooden member of octagonal form of the same size as the outer dimensions of the container to which it is applied. This top wall is placed upon the upper ends of the side walls 16 and is then secured in place by means of a metallic rim 26 of octagonal form having a plurality of depending portions 26^a adapted to conform to and fit against the outer surfaces of the upper wall sections 16, and also a series of inwardly extending transversely corrugated flange portions 26^b which overlie and normally engage the upper surface of the top wall 25. This metallic rim 26 is placed over the cover 25 and then the rim is secured to the outer wall sections of the container by driving nails 27 through apertures 26^c formed in the portions 26^a of the rim.

The depending portions 26^a of the side walls 35 are outwardly flared adjacent their lower edges as shown at 26^d and the apertures 26^c are preferably punched through the metal at the upper edge of this outwardly flared portion. The corrugations 26^e which are formed in the flanges 40 26^b extend transversely of the flanges and extend parallel to each other through the intermediate parts of each flange but adjacent the apices 26^f of the rim, these corrugations are tapered, that is, they are flared outwardly from 45 their inner ends, thus accommodating the metal of the inwardly extending flanges which is brought together at the apices of the rim by reason of the angularity of adjacent sections of the body portions 26^a. This rim may be formed 50 from a continuous strip of sheet metal, as described and claimed in the co-pending application of Chester M. MacChesney and Allen B. Wilson Serial No. 730,412, filed June 13, 1934, and

the overlapping ends of the strip are provided with registering holes which are engaged by rivets 29 to form a complete annular rim. This rim may be conveniently placed over the outer polygonal walls of the container, due to the outward flaring of the bottom portions of the sections 26^a. The corrugated flanges 26^b then rest upon the adjacent head or end wall 25 and when the nails 27 have been driven through the holes 26^c into the wall portions 16 of the container, the head is held in fixed relationship to the outer walls and both the head and the walls are reinforced by the surrounding metallic rim. 5 10 15

Although one form of the improved rim has been shown and described by way of illustration, 15 it will be understood that it may be constructed in various other embodiments coming within the scope of the appended claims.

I claim:

1. The combination in a container, of outer 20 walls arranged in the form of a polygon, an end wall, and a metal rim extending around and conforming to said outer walls and having a transversely corrugated inwardly extending flange seated against said end wall, some of said corrugations of said flange being tapered longitudinally. 25

2. The combination in a container, of outer 30 walls arranged in the form of a polygon, an end wall, and a metal rim extending around and conforming to said outer walls and having a transversely corrugated inwardly extending flange seated against said end wall, said corrugations of said flange being tapered longitudinally adjacent the apices of the polygon. 35

3. A rim for containers comprising an annular metal member having a body portion of polygonal form adapted to conform to the sides of a container of polygonal cross-section, said body portion having an annular inwardly extending flange 40 provided with transverse corrugations, said corrugations being tapered longitudinally. 40

4. A rim for containers comprising an annular metal member having a body portion of polygonal form adapted to conform to the sides of a 45 container of polygonal cross-section, said body portion having an annular inwardly extending flange provided with transverse corrugations, said corrugations being tapered longitudinally in one direction adjacent the apices of the polygon 50 and being substantially parallel to each other at intermediate points.

CHESTER M. MACCHESNEY.
